UNITED STATES PATENT OFFICE.

GEORGE W. FROHLICH, OF CHICAGO, ILLINOIS.

DRAW-BENCH.

1,172,448.

Specification of Letters Patent. Patented Feb. 22, 1916.

Application filed February 16, 1915. Serial No. 8,450.

To all whom it may concern:

Be it known that I, GEORGE W. FROHLICH, a citizen of the United States, and a resident of the city of Chicago, in the county of 5 Cook and State of Illinois, have invented a certain new and useful Improvement in Draw-Benches; and I do hereby declare that the following description of my said invention, taken in connection with the accompanying sheets of drawings, forms a full, clear, and exact specification, which will enable others skilled in the arts to which my said invention appertains or with which it is most nearly connected to make and use 15 the same.

This invention has general reference to draw-benches, and more particularly to that class of draw-benches which are now employed for drawing, from strip-sheet metal, 20 formed bars, such as bars for sheet metal doors, window casings, window sashes, bars for sky-lights and analogous work; and it has for its object the construction of such a machine in which a multiplicity of drawing 25 instrumentalities are combined in a single structure, and in which the gripping tongs or nippers, by which the strips are being pulled on each of the several instrumentalities are automatically released when they 30 reach the end or terminal of the structure, and are then automatically returned to a single receptacle at the initial, or starting point of the machine. To accomplish these results, I construct this machine in its preferred embodiment, as shown in the drawings 35 already mentioned, in which—

Figure 1, is a plan of this improved draw-bench. Fig. 2, is a plan of a fragment of the endless drawing belt and one of the gripping nippers. Fig. 3, is a side-elevation of the mechanism illustrated in Fig. 2. Fig. 4, is a perspective view of the means employed for disconnecting the gripping nippers from the endless drawing belt. Fig. 5, is an end- 40 view of the complete machine a portion of the conveying troughs being shown in section. Fig. 6, is a side-elevation of the complete machine. Fig. 7, is a sectional view of a portion of the machine taken on line 45 7—7 of Fig. 5. Fig. 8, is a transverse sectional view taken on line 8—8 of Fig. 6. Fig. 9, is a sectional elevation of a fragment of the machine looking toward the forward end, on line 9—9 of Fig. 10, and showing 50 one of the gripping tongs in the act of being disengaged from the endless chain belt ready

to drop by gravity into the chute through which it passes to reach the conveyer belt which returns this gripping tong to the starting end of the machine. Fig. 10, is a 60 sectional plan view on line 10—10, of Fig. 5, of the rear portion of the machine, the endless chain belts, and the conveyer belt being omitted, and also showing a modified form of driving mechanism for these endless 65 belts.

Like parts are designated by the same characters and symbols of reference in all the various figures.

In the manufacture of shaped bars formed 70 from sheet metal cut into strips of proper width and then passed through suitable shaping, or drawing, dies, these bars are made of considerable length, which are afterward cut to proper dimension. In the 75 drawings I have, therefore, shown the machine broken, to indicate that the length thereof may be varied to accommodate varying conditions. As shown in Fig. 1, this machine includes a multiplicity of like 80 drawing-devices arranged side-by-side in parallel spaced relation, there being in the preferred arrangement and construction, four of these strip-drawing devices, two on each side of a centrally disposed conveying 85 mechanism by which the gripping tongs of the entire series of drawing devices are returned to a receiving receptacle common to all the drawing devices. As arranged, the two strip-drawing devices at one side of 90 the central, gripping-tongs-returning mechanism, are elevated, at their rear ends, above those of the opposing set of drawing mechanisms, as will hereinafter more fully appear.

95 A, B, in the drawings designate two of the draw-benches located at the left side of the machine, and as well, those on the right side thereof. These benches, except where otherwise stated are alike and a description 100 of one of these drawing-devices will therefore, equally apply to all the others.

That portion or section of the machine carrying the drawing devices A, B, includes, as best shown in Fig. 8, two pairs of side-walls, 8, 9, and 10, 11, respectively, the pairs of side walls being in parallel spaced relation, with a wider space between the walls 10, and 11, as will be hereinafter referred to. The side-wall 8 is secured, at its upper margin, to a longitudinal rail 14, while the side-wall 9 is similarly secured to a longitudinal 105 110

rail 15, both rails extending the entire length of the machine; and they are supported upon suitable supports or legs 16, 17, properly braced by struts 18, wherever necessary or 5 desirable. The members 8, 10, and 11, 9, are connected to each other adjacent to their upper margins by longitudinal floors or running-boards, 19, 20, respectively, while the inner side-walls 10, 11, are connected at 10 their lower edges by a bottom-board 21, from which rises, medially between these side-walls a partition 22, thereby affording two troughs C, D, designed to receive the drawn strip-bars after their completion. 15 The spaces above the running boards and the side-walls afford channels wherein endless chain belts 23, 24, are constructed to move, said chain belts being trained over guiding pulleys 25, 26, located at the forward end of 20 the machine, said pulleys being mounted on shafts 27, 28, rotating in bearings 29, 30, secured to the forward supports 16, 17.

At the rear end of the machine there is, 25 transversely located, a shaft 31, Figs. 1, 5, 6, and 7, rotating in suitable bearings, 80, and carrying, in alinement with the two endless draw-chains 23, 24, two sprocket wheels, 32, over which the two endless chain belts 23, 24, are also trained and by which these belts 30 are driven. At the rear end of the frame structure on which the endless chain belts are mounted, there is a downwardly directed chute, 34, which leads from the left hand side of the frame structure to a central 35 channel 35, which channel comprises two side-walls 36, 37, secured to the opposing supporting members 17, 17, and a bottom or runway, 38. At the forward end of the frame structure there is journaled an idler wheel, 39, Fig. 6, and at the rear end of said frame structure there is mounted a driving sprocket 40, secured to a shaft, 41, having 40 bearings in a housing 42. On this shaft 41 there is, furthermore, mounted a driven pulley 43, to which rotative motion is communicated by a belt 44, as will hereinafter more fully appear. Over this driving sprocket 40 and the idler wheel 39 there is 45 trained an endless link-conveyer belt 45, which carries at intervals cross-bars or paddles, 46, the object of which I shall now describe.

Figs. 2 and 3 show, on an increased scale, 50 a pair of toggle-jointed gripping tongs E, the two pivotally connected members 47, 48, of which, are link-connected by members 49, 50, which at adjacent terminals are pivoted to a bar 51, which has a downwardly extending hook 52, constructed to engage any 55 one of the cross-members 53, of the link-belt 23. The members 51, and 47 of the gripping tongs E are preferably provided with knobs or handlebars, 54, for convenience in handling the same.

60 As stated in the preamble to this specifi-

cation, the two sets of elements of this machine are substantially alike except that the set of elements at the right of the same (being the one shown at the left of Fig. 8) inclines upwardly toward the rear end of the 70 structure, the object, or reason for which is to provide for a chute, 55 leading from the ends of the two endless chain belts 23, 24, downwardly and crosswise toward the central channel 35, and thence by a forwardly leading channel or chute 56, above the lower terminal of the chute 34 leading from the left side strip-drawing instrumentalities A, B, to said central channel 35. By thus conducting the gripping tongs from one set of strip-drawing devices to the return conveyer belt, above, and in advance of those coming from the other set of strip-drawing devices. I derive the result that two gripping tongs E cannot drop upon said 80 conveyer belt at the same place, although two of said gripping tongs E may fall thereon at the same time, which, were there more than one pair of gripping tongs E dropping on the conveyer belt at the same 90 time and the same place, might cause them to wedge themselves in the conveying channel 35, and thereby result in breakage and possible damage to, and interruption of the operation of the moving parts. This is a 95 very desirable and important feature of this machine, contributing as it does, its share toward the successful and economical operation of the same.

The operation of the devices heretofore 100 described is, essentially, as follows: At the forward end of the machine there are provided suitable means 57, Figs. 1, and 6, to receive a roll of slotted sheet metal the end of which is led upwardly over a guiding roller 105 58, mounted in suitable bearings 59, and thence passed through one or more shaping dies 60. A pair of gripping tongs E is now hitched to the end of said sheet metal strip or ribbon 61, and these nippers, by the hook 110 52 thereon, attached to the proper endless chain belt 23, it being understood that the upper stretches of all these said belts travel toward the rear end of the structure and thus pull a length of formed sheet metal 115 bars, almost as long as the entire structure. Near the rear end of the structure, and located on the upper marginal of the side-walls 8, 9, there are located inclined planes 62, one of which is shown in detail in Fig. 4; 120 and near their rear ends, the longitudinal members 10, 11, have their inner upper margins beveled or chamfered as illustrated at 63, whereby, when a pair of gripping tongs approaches the rear end of the structure, one side of the said gripping tongs will move upwardly on said incline 62 and thereby be tilted, thus disengaging the hook 125 52 from the endless chain, and slide downwardly, by gravity, over the chamfered 130

edge 63 into the chute 34, or the chute 55, as the case may be, and then drop on the upper stretch of the conveyer belt 45, which moves toward the forward end of the structure, 5 and where one of the cross-bars 46 thereon will engage the gripping tongs and push the same forward until the forward end of the structure is reached where said gripping tongs will drop into a receiver 64, occupying 10 the forward terminal of the channel 35. The shafts 31, by which the endless chain belts are operated, carry at their outer terminals pulleys, 65, 66; and above the rear end of the machinery there is located a counter shaft, 67, rotating in hangers 68, 69, which counter shaft receives rotary motion from any suitable prime motor, not shown. Near the terminals of this counter shaft there are mounted pulleys, 70, 71, over 15 which, and the pulleys 65, 66, belts 72, 73 are trained to communicate rotary motion to said shafts 31. Upon counter shaft 67 is mounted a further pulley 74; and on a counter shaft 75, rotating in suitable 20 hangers 76, is mounted a driven pulley 77, over which, and the pulley 74, a belt 78 is trained to communicate rotary movement to said counter shaft 75. Upon this latter counter shaft there is also mounted a driving pulley 79, by which, and the belt 44 already referred to, rotary movement is transmitted to the shaft 41, all as clearly illustrated in Figs. 5, and 6.

Attention is now directed to the fact that 35 in the structure as described, a series of strip-drawing devices are simultaneously operated, and that a single operator is capable of readily attending to the entire series of these devices to keep them supplied with 40 strip-metal, and that all the gripping tongs or nippers from the entire series of strip-drawing devices are automatically returned to a single receiver, within easy reach of said operator, the result being that long bars 45 of shaped sheet metal may be formed on this machine, the cost for labor of which is nominal. The long strips are collected in the troughs C, D, and the farther ends of these troughs may be left open so that the long 50 bars may be withdrawn therefrom, to be cut to shorter lengths by suitable machinery not shown, located adjacent to the rear end of the structure. As shown the shaft 31 is directly driven by the comparatively large 55 driving pulley 65, but this construction may be modified, as shown at the right of Fig. 10, by substituting for the driving pulley, a spur gear wheel, 81, wherewith meshes a gear pinion 82, mounted on a shaft 83, together with a smaller driving pulley 84, which will be rotated from the counter shaft 67, in the same manner as the larger pulley 65, in an obvious manner.

It will now be understood that when the 65 gripping tongs reach and move on the in-

cline 62, the connection with the endless chain belt will be severed and the jaws of these tongs will open automatically and disconnect from the drawn and shaped bar of strip sheet metal, which bar will then be cut off behind, or in rear of the drawing dies, and another pair of gripping tongs applied to that portion of said strip adjacent to said drawing dies, and then the cycle of operations repeated as often as bars are to be produced, in the same dies. These dies are removable and others may be substituted therefor in a manner now common in bar drawing devices. The object of dividing the space between two sets of bar drawing devices by the partition 22, is to afford a separate trough for each bar drawing instrumentality which is desirable when one instrumentality draws a bar, different in contour from the other, to prevent the bars being 75 mixed, but it is evident that this partition may be dispensed with, if desired, without seriously impairing the usefulness of this machine. And in order that this machine may comply with the laws of the various 80 States for the protection of workmen from injury by moving parts, I surround the pulleys 65, 66, with suitable casings, 85, 86, as clearly shown in Figs. 1, 5, and 6.

Attention is now directed to the fact that 85 in drawing heavy material, the travel of the gripping tongs E, up the incline plane 62 is often insufficient to release the hook 52, from engagement with the endless chain, by reason of the pressure of contact of said 90 hook 52, against said endless chain link 53. Thus, in order to insure a positive release of this hook 52 at the proper time, it may be added that the sprocket 32 or 32^a is so located, that as the particular tooth thereof, 95 when it enters into the link against which the hook 52 impinges, will force said hook 52 upwardly to a full release at the proper time in an obvious manner.

I have heretofore described with considerable minuteness the preferred embodiment of my invention, and the best method of carrying the same into effect; but I desire it to be understood that many of these details may be varied, if desired, without departing from the scope of my invention as defined in the appended claims.

Having thus fully described my invention I claim as new and desire to secure to myself by Letters Patent of the United States:

1. A machine for drawing shaped bars of sheet metal from stripped stock, including a series of sets of drawing instrumentalities, one set of such instrumentalities being on a substantially horizontal plane, the other set being rearwardly and upwardly inclined, separate chutes leading from each set of drawing instrumentalities downwardly and toward each other, the terminal of one of

said chutes overlying the terminal of the other of said chutes and ending in front of the end of the latter chute, a channel between adjacent sets of said instrumentalities 5 into which the aforesaid chutes lead, an endless conveyer-belt in said channel, a receptacle at the forward end of said channel, means for operating the drawing instrumentalities, and means for operating said 10 endless conveyer-belt.

2. In a machine for drawing shaped bars of sheet metal from stripped stock, the combination, of a suitable frame structure, an endless chain-belt movably located in said 15 frame structure, means, for drawing said stripped stock along said frame structure, by said endless chain-belt, including a pair of gripping tongs, constructed for removable connection with said endless chain, 20 means adjacent the rear end of said frame structure constructed to disengage said gripping tongs, a chute adjacent the rear end of said frame structure, an endless conveyer-belt in said frame structure, said conveyer-belt moving in a direction opposed to that of 25 said endless chain-belt, said chute terminating above, and in axial line with, said endless conveyer-belt, a receptacle at the forward end of said frame structure, said receptacle being in communication with said 30 endless conveyer-belt, and means for operating said endless chain-belt and the endless conveyer-belt.

3. In a machine of the nature described, 35 a pair of formed bar drawing instrumentalities, including, in combination, a suitable frame structure, a pair of channels in said frame structure in parallel spaced relation, an endless-chain-belt in each of said 40 channels, a trough between said channels constructed to receive the, formed bars, a chute at the ends of said channels, a further channel adjacent to the heretofore mentioned two channels, said chute terminating 45 in the latter channel, an endless-conveyer-belt in the latter channel, gripping tongs, said gripping tongs being provided with means for removable attachment to said endless-chain-belts, an inclined plane at the 50 rear end of each of the pair of channels constructed to tilt said gripping tongs to disconnect said gripping tongs from said endless-chain-belts to drop through said chute onto the endless-conveyer-belt by gravity, and means for operating the two endless-chain-belts and the endless conveyer-belt. 55

4. A machine for drawing shaped bars from ribbon sheet metal, comprising, a multiplicity of sets of strip drawing mechanisms, each set of such mechanisms including an endless chain-belt, means constructed to operate the endless chain-belts in each set simultaneously, gripping tongs for each mechanism in each set, said gripping tongs 60 being provided with means for detachable connection with said endless chain-belts, means on each individual strip drawing mechanism constructed to tilt said gripping tongs to disconnect them from said endless 65 chain-belts, a channel common to all of the sets of strip drawing mechanisms, an endless conveyer-belt in said channel, a chute, leading from one set of said strip drawing mechanisms to said endless conveyer-belt, a further chute leading from the second set 70 of strip drawing mechanisms to said endless conveyer-belt, said latter chute terminating in advance of the terminal of said first mentioned chute, and means for operating the endless conveyer-belt in the opposite 75 direction from that in which the entire series of endless chain-belts are moving.

5. In a machine for drawing shaped bars from ribbon sheet metal, the combination 80 of a suitable frame structure said frame structure including, two longitudinal walls in parallel spaced relation said walls being connected at their lower margins by a transverse bottom to afford a channel, an endless chain-belt, the upper stretch of said chain-belt being constructed to move rearwardly in said channel, a drawing die at the forward terminal of said channel, an inclined plane adjacent the farther terminal 85 of said channel, said inclined plane being located at the upper margin of one of said walls, the upper outer margin of the opposing wall being chamfered, a further channel adjacent the latter wall, an endless conveyer-belt in the latter channel, a chute connecting the two aforementioned channels, said chute terminating above the upper stretch 90 of said endless conveyer-belt, and means for operating the said endless chain-belt and 95 the said endless conveyer-belt.

In testimony that I claim the foregoing as my invention, I have hereunto set my hand in the presence of two subscribing witnesses.

GEORGE W. FROHLICH.

In the presence of—
C. S. STARK,
W. HARDING.
